ADJUSTABLE FINGER BAR FOR SHEAR MACHINES

Salvatore Biazz, San Jose, Calif., assignor of one-half to August E. Azzarello, San Jose, Calif.

Application October 11, 1934, Serial No. 747,950

5 Claims. (Cl. 271—54)

This invention relates to improvements in the art of metal working and pertains particularly to an improved mechanism for feeding sheet metal to a shear machine.

5 In the operation of a scroll metal shear machine, sheets of metal are fed continuously for a predetermined distance toward a cutting die and the metal is then taken up by reciprocating fingers and moved in a series of steps toward and 10 beneath the die, the first step locating the metal upon the die table for squaring up, the second step moving the metal into position for a trim cut by the die, and the next succeeding steps moving the metal a predetermined distance each 15 time for a strip of metal of predetermined size to be cut by the die. In the machines of the type at present in use, all of the finger members which give the step by step movement to the sheet of metal move as a unit and since it is necessary 20 that the sheet metal be moved a greater distance at each step following the first two steps, the fingers which impart the first two step movements to the metal must move a relatively great distance back of the trailing edge of the metal 25 sheet with the result that as they come forward, they strike the sheet with such force that the edge is bent or curved and each succeeding time that a finger hits this edge a little more bend is given thereto, with the result that the pieces or strips 30 cut by the die after the trim cut are not all of one size as they should be. This results in a waste of material.

The primary object of the present invention is to avoid the disadvantages now present in metal 35 shearing machines, as above outlined, by providing a finger mechanism whereby the fingers which impart the first two movements to the sheet metal, while being reciprocated by the same mechanism which operates the other fingers, 40 are adapted to have movement relative to the said other fingers and are so controlled that they need only move back far enough to engage the rear edge of the sheet metal so that in their forward movements, the said edge will not be hit with 45 sufficient force to bend the metal.

A further object of the invention is to provide mechanism of the above described character which may be added to the present metal shearing machine without making any material 50 changes in the same.

The invention will be best understood from a consideration of the following detailed description taken in connection with the accompanying drawing forming part of this specification, with 55 the understanding, however, that the invention

is not confined to any strict conformity with the showing of the drawing but may be changed or modified so long as such changes or modifications mark no material departure from the salient features of the invention as expressed in the appended claims.

In the drawing:

Figure 1 is a view in side elevation of a portion of the sheet metal table of a shear machine, a part of which is broken away to show a portion of the present structure and the mechanism embodying the new structure which constitutes the present invention.

Figure 2 is a view in top plan of the portion of the sheet metal table shown in Figure 1, the center part of which has been broken away.

Figure 3 is a sectional view taken substantially upon the line 3—3 of Figure 2.

Figure 4 is a sectional view taken on the line 4—4 of Figure 3.

Figure 5 is a view in top plan of the sheet metal engaging finger which is shown in side elevation in Figure 4.

Referring to the drawing, the numeral 1 indicates generally the frame or sheet metal table of a shear machine as now manufactured, which table is provided with the spaced parallel channels 2, which are disposed at the sides of the table, each of these channels at its rear end extending completely through the table through a portion of the length of the channel to form a slot 2', as is clearly illustrated in Figures 1 and 2.

The bottom of each of the channels is indicated by the numeral 3, these bottoms constituting a bearing surface for a reciprocating bar 4 which at its rear end is formed to provide the downwardly extending terminus 4'. Each of these bars 4 has extending longitudinally thereof and in its upper surface, the T-slot 4'' which receives, in the machines at present in use, an appropriately formed portion of an adjustably secured finger 4'''.

These fingers 4''' operate, with others which are removed for the application of the present invention as will be hereinafter described, to engage a body of sheet metal which is carried onto the table 1 by conveyor chains, not illustrated, and carry it forward to the die portion of the machine.

The reciprocation of the finger carrying bars 4 is effected by means of connecting rods 5, each of which is pivotally coupled at one end, as indicated at 6, with the depending portion 4' of a bar 4, and at its other end is pivotally connected, as indicated at 7, with the upper end of a crank 55

lever 8 which is secured to and carried by a rock shaft 9 which extends transversely of the machine and is actuated through connection with a suitable portion of the operating mechanism 5 thereof.

The present invention comprises an auxiliary finger bar 10 for each bar 4. Each of these auxiliary bars 10 is in transverse section substantially H-shaped, so that when it is disposed on its 10 side, it has parallel top and bottom lateral flanges as is clearly shown in Figure 3, and the bottom ones of these lateral flanges and a portion of the web part of the bar are slidably disposed in a T-slot 4" of a bar 4. The top flanged portion of 15 each auxiliary bar 10 projects above its carrier bar 4, as shown in Figure 3, for the purpose hereinafter to be set forth.

At the rear end of each auxiliary bar 10 is a 20 depending web 13 which has pivotally connected therewith, as at 14, an end of a connecting rod 15, the other end of which passes through a swivel block 16 carried by an auxiliary rocker arm 17 which is secured to and vertically supported by the shaft 19 which extends transversely of the 25 machine and is supported in rocker bearings 20.

The end of the rod 15 which passes through the swivel block 16 is threaded and receives thereon lock nuts 16' which are placed upon either side of the block 16 so that the proper adjustment of 30 the rod 15 may be made relative to the rocker arm 17.

The rocker arm 17 is coupled with the arm 8 by means of the coupling rod 21, the rod being pivotally connected at one end, as at 22, with the 35 intermediate portion of the arm 8 while at its other end, it carries a bolt or pin 18 which is secured in a slot 31 in and extending longitudinally of the arm 17. By means of this slot, the end of the rod 21 which is joined to the arm 17, 40 may be shifted longitudinally of this arm and the throw of the arm thus changed as found necessary.

The numerals 11 and 12 indicate the sheet metal engaging fingers which are adjustably secured 45 on the auxiliary finger bars 10. These fingers 11 and 12 are the first two fingers upon the standard finger bar 4, one of which on each bar 4 engages the sheet metal to move it into position to be squared up while the other engages 50 the metal to move it into position for the trim cut. These are transferred from the standard bars 4 to the auxiliary bars 10 and as shown, they are carried upon blocks 23 and 24 (Fig. 2), each of which blocks has upon its outer side the laterally projecting flange 25.

A pivot screw 26 joins the finger to the side 60 of the block adjacent the flange 25 so that the rear end of the finger will abut this flange when the forward end is raised in the manner illustrated in Figure 4, and the under side of each block is provided with a T-slot for the reception of the top of a finger bar 10, as illustrated in Figure 3.

A spring 29 is mounted upon each flange 25 adjacent its forward end and beneath the forward end of the finger adjacent thereto, so that it will abut the under side of the finger and normally urge it to the raised position in which it is shown in Figure 4, the forward or raised end of each finger being under cut or notched, as indicated by the numeral 30, for its secure engagement over the edge of a sheet of metal. This notched portion 30 when the finger is raised, 70 projects a sufficient distance above the top sur-

face of the table 1 to engage the sheets of metal thereon.

From the foregoing description, it will be apparent that heretofore when all of the fingers were carried upon the bar 4, the two fingers 5 nearest the rear end of the bar 4 were required to move a relatively great distance back of the edge of the sheet metal with which they had to engage, because of the fact that the next succeeding fingers were required to move the sheet 10 metal a materially greater distance than the first two fingers, and this required that the throw of the arm 8 and the movement of the bar 4 be great enough to take care of the greatest movement which had to be imparted to the sheet of 15 metal. The first two fingers only moved the metal a short distance for the purpose, as previously stated, of first positioning the metal for squaring up and second, for positioning the metal for a trimming cut. As a result of the higher 20 speed than fingers 11 and 12 of this invention, which the two rear fingers had to have prior to engaging the edge of the sheet metal so that their movement of the metal would not be very great, they struck the metal with considerable force 25 and this resulted in the bending of the same.

With the present mechanism, the movement of the auxiliary finger bars 10 is relative to the movement of the bars 4 although they are joined together and they both move at the same time 30 and under the influence of the same actuating arms. It will be readily apparent that the throw of the rods 5 will be greater than that of the rods 21 and, therefore, the fingers 4''' can continue to have the full sweep necessary to move 35 the sheets the required distance after the same have been shifted forward by the first two sets of fingers and the first two sets of fingers need only move far enough back to permit them to rise up under the influence of the springs 29 directly behind and in relatively close proximity to the rear edges of the sheets of metal. As their movement relative to the edge of the metal sheets need not be greater than the movement of the fingers 4''' relative to the rear edges of 45 the sheets, it will be apparent that they will not strike the metal with any considerable amount of force and, therefore, the bending of the metal will not occur.

It will be obvious to those skilled in the art 50 that since the sheets of metal lie flat upon the table 1, the fingers 4''' 11 and 12 will be depressed through contact with the under side of the sheet and will snap up behind the rear edge of the same after they have passed it. 55

It will also be apparent that while fixed adjustments of the bars 10 may be made by loosening the lock nuts 16' and shifting the rod 15 through the swivel block 16, the auxiliary finger bars 10 may also be further finely adjusted 60 quickly and while the machine is in operation by sliding the pivot bolt 18 of the long coupling bar 21 upwardly or downwardly in its slot 31.

What is claimed is:—

1. In a machine of the character described, 65 including a table, a finger carrying bar mounted for longitudinal movement longitudinally of the table and having a channel therein, a rocking lever and a coupling bar between the rocking lever and the first bar; an auxiliary bar slidably mounted in the channel of the first bar, fingers carried by the auxiliary bar for engaging a body on the table, a second rocking lever, a link connection between the second lever and the auxiliary bar, and a link bar coupling the said levers 70

and connected with the first lever at a point nearer its center of oscillation than the coupling bar whereby the first mentioned bar will have a greater throw than the auxillary bar.

- 5 2. In a machine of the character described, having a table, a finger carrying bar mounted for longitudinal reciprocation relative to the table, a rocking power transmitting lever and a coupling bar between the lever and the finger bar; an auxillary bar mounted for longitudinal reciprocation relative to the table and parallel with the first bar, a second rocking lever, a link bar coupling the rocking levers together, a coupling between the second rocking lever and the auxillary bar, and means for shifting the point of connection between one end of the link bar and the adjacent rocking lever whereby relative movement between the finger carrying bars may be controlled.
- 10 3. In a machine of the character described, including a table, a bar mounted for longitudinal reciprocation relative to the table, fingers carried by the bar for engaging a body on the table and mechanism for reciprocating said bar; an auxillary bar mounted for longitudinal reciprocatory movement in a path paralleling the first bar, body engaging fingers carried by the auxillary bar, said auxillary bar extending at one end beyond an end of the first bar, and mechanism connected with the auxillary bar and reciprocating the same simultaneously with and in the same direction as the first bar and moving the same to a different extent from the first bar.
- 15 4. In a machine of the character described,

including a table, a finger carrying bar mounted for longitudinal movement relative to the table, a rocking arm and a coupling between the rocking arm and the finger bar; an auxillary bar mounted for longitudinal movement in a path paralleling the first bar, body engaging fingers carried by the auxillary bar, a second rocking arm, a link coupling the auxillary bar with the second rocking arm and having longitudinally adjustable connection therewith, a link bar pivotally attached at one end to one of said arms, the other of the arms having a slot longitudinally therein, and a securing element pivotally connecting the other end of the last mentioned link bar with the slotted bar and engaging in the slot thereof for facilitating the changing of the throw of the slotted arm.

- 20 5. In a machine of the character described, including a table, a material engaging finger carrying bar mounted for longitudinal movement longitudinally of the table and mechanism connected with the bar to give the same a forward and backward movement; an auxillary bar mounted for longitudinal movement in a parallel path with the first bar, a material engaging finger carried by the auxillary bar, and mechanism coupling the auxillary bar with the first bar operating means and acting to move the bar simultaneously and to move the auxillary bar at a slower speed than the first bar whereby the fingers of the two bars when moving forwardly will move apart and will move together when the bars are moving rearwardly.
